SALTS OF 1,1-DIMETHYL-3-PYRROLIDYL
PHENYL-2-THIENYLGLYCOLATE

Cameron Ainsworth and Charles W. Ryan, Indianapolis, Ind., assignors to Eli Lilly and Company, Indianapolis, Ind., a corporation of Indiana
No Drawing. Filed Dec. 18, 1961, Ser. No. 160,308
4 Claims. (Cl. 260—326.3)

This application is a continuation-in-part of copending application Serial No. 47,135, filed August 3, 1960, now abandoned.

This invention relates to alkyl-substituted 3-pyrrolidyl esters, and to their acid addition compounds and quaternary ammonium derivatives.

The alkyl-substituted 3-pyrrolidyl ester bases of this invention are represented by the following formula:

wherein the various substituent groups are as follows:

R is a lower alkyl radical having from 1 to 4 carbon atoms.

R¹ and R² are hydrogen or lower alkyl radicals having from 1 to 4 carbon atoms, substituted at positions 2, 4, or 5, of the pyrrolidine ring. Where R¹ and R² are both alkyl radicals, both can be at one position, viz., position 2, 4, or 5 or they can be at different positions.

The lower alkyl radicals referred to hereinabove can be methyl, ethyl, n-propyl, isopropyl, n-butyl, 1-methylpropyl, isobutyl, or t-butyl.

R³ is phenyl, chlorophenyl, bromophenyl, methoxyphenyl, thiienyl, or a cycloalkyl radical having from 5 to 7 carbon atoms.

From the foregoing, it will be apparent that the pyrrolidine ring can have zero, one, or two alkyl substituents.

The pyrrolidyl esters represented by the above formula are generally colorless liquids soluble in most organic solvents but relatively insoluble in water. Among such esters are the following:

1-methyl-3-pyrrolidyl bis(2-thienyl)glycolate
1-ethyl-3-pyrrolidyl phenyl-2-thienylglycolate
1-n-propyl-3-pyrrolidyl o-chlorophenyl-2-thienylglycolate
1-isopropyl-3-pyrrolidyl p-bromophenyl-3-thienylglycolate
1-n-butyl-3-pyrrolidyl m-methoxyphenyl-2-thienylglycolate

1-isobutyl-3-pyrrolidyl cyclopentyl-2-thienylglycolate
1-sec-butyl-3-pyrrolidyl cyclohexyl-3-thienylglycolate
1-tert-butyl-3-pyrrolidyl cycloheptyl-2-thienylglycolate
1,5-dimethyl-3-pyrrolidyl phenyl-2-thienylglycolate
1,2,2-trimethyl-3-pyrrolidyl phenyl-2-thienylglycolate
1,4-dimethyl-3-pyrrolidyl phenyl-2-thienylglycolate
1-tert-butyl-3-pyrrolidyl bis(2-thienyl)glycolate
1-methyl-5-n-propyl-3-pyrrolidyl bis(2-thienyl)glycolate
1-methyl-5-isopropyl-3-pyrrolidyl phenyl-3-thienylglycolate
1-methyl-5-tert-butyl-3-pyrrolidyl bis(3-thienyl)glycolate

Preferred compositions of the present invention have R¹ and R² chosen from hydrogen, methyl, and ethyl, attached to the pyrrolidine ring at the 2 and/or 5 positions, with either phenyl or thiienyl in the R³ position. Among such compositions are 1-methyl-3-pyrrolidyl phenyl-2-

2

thienylglycolate, 1,5-dimethyl-3-pyrrolidyl bis(2-thienyl)glycolate, 1,5,5-trimethyl-3-pyrrolidyl phenyl-3-thienylglycolate, and 1,2-dimethyl-3-pyrrolidyl bis(3-thienyl)glycolate.

Also included within the scope of this invention are the acid addition salts (e.g., the hydrochloride, the hydrobromide, the sulfate, the phosphate, and the like) of the pyrrolidyl esters represented by the above formula, as well as the quaternary compounds derivable therefrom. The said quaternary compounds can be represented by the following formula:

wherein R, R¹, R², and R³ are in accordance with the above definitions thereof, R⁴ is methyl or ethyl, and X⁻ is a pharmaceutically acceptable anion such as hydroxide, chloride, bromide, iodide, sulfate, nitrate, phosphate, or the like.

Presently preferred quaternary compounds coming within the ambit of this invention include 1-methyl-3-pyrrolidyl phenyl-2-thienylglycolate methobromide, 1-methyl-3-pyrrolidyl phenyl-2-thienylglycolate methochloride, 1-methyl-3-pyrrolidyl phenyl-2-thienylglycolate ethochloride, 1,5-dimethyl-3-pyrrolidyl bis(2-thienyl)glycolate methosulfate, 1,5,5-trimethyl-3-pyrrolidyl phenyl-3-thienylglycolate ethophosphate, 1,2-dimethyl-3-pyrrolidyl bis(3-thienyl)glycolate 1-methyl hydroxide, and the like.

The alkyl-substituted 3-pyrrolidyl esters are prepared, generally speaking, by the reaction of the appropriate alkyl-substituted 3-pyrrolidinol with a lower alkyl ester of an α -hydroxy α -thienyl carboxylic acid having the required R³ substituent.

The alkyl-substituted 3-pyrrolidinol compounds can be prepared employing an appropriate substituted diester of a dicarboxyalkylamine and sodium hydride in a Dieckman cyclization reaction followed successively by decarboxylation and reduction of the ketone produced thereby. Concentrated hydrochloric acid can be employed as the decarboxylating agent and lithium aluminum hydride or sodium borohydride as the reducing agent. The following illustration of the procedure, hereinafter referred to as "Pyrrolidinol Procedure I," shows the preparation of 1-methyl-3-pyrrolidinol:

Alternatively, the alkyl-substituted 3-pyrrolidinols can be prepared by the reaction of the appropriate dihalo monohydroxy alkanol and amine as described by Lunsford in U.S. Patent No. 2,830,997 (April 15, 1958), e.g., in Example 1 thereof, in which n-butylamine and 1,4-dibromo-2-butanol are reacted to provide N-butyl-3-pyrroli-

dinol. This alternative procedure is hereinafter referred to as "Pyrrolidinol Procedure II."

In the preparation of the esters of alkyl-substituted 3-pyrrolidinols, an appropriate alkyl-substituted 3-pyrrolidinol and a lower alkyl ester of an α -hydroxy α -thienyl carboxylic acid having the desired R^3 substituent are added in about equimolar quantities to an inert mutual solvent, for example, n-heptane. The mixture is heated to reflux temperature, at which time a small quantity of a basic catalyst such as sodium methylate is desirably added, and refluxing is continued. Customarily, a reflux period of about three hours is sufficient to complete the reaction. It has been found desirable to remove the simple alcohol by-product as it is formed, suitably by incorporating a Dean-Stark trap in the reflux apparatus. The resulting alkyl-substituted 3-pyrrolidinyl ester can be recovered from the reaction mixture as one of its acid addition salts by extracting the reaction mixture with an aqueous solution of the appropriate acid. The acid addition salt of the ester can be obtained in crude form by evaporating the aqueous extract thereof to dryness.

The acid addition salt can be further purified if desired by reconverting the salt to the free ester, dissolving the free ester in an inert solvent such as ethyl acetate, and reprecipitating the ester as its acid addition salt, e.g., by adding an anhydrous ethanolic solution of hydrogen chloride. The free ester can then be obtained if desired by basifying an aqueous solution of the acid addition salt with a suitable base such as potassium carbonate, and then extracting the basified mixture with a water-immiscible solvent in which the free base is soluble, such as benzene, chloroform, or ether. The organic solvent extract of the free base is washed thoroughly with water and dried, and the base is recovered from the dried extract by evaporating or distilling the solvent.

The quaternary derivatives (e.g., the methobromide salts) of the various alkyl-substituted 3-pyrrolidinyl esters can be obtained by dissolving a quantity of the appropriate ester base in an inert mutual solvent such as benzene or methyl ethyl ketone and introducing the appropriate quaternary salt-forming agent into the solution, e.g., methyl bromide, methyl chloride, ethyl iodide, methyl sulfate, or the like. The reaction is preferably carried out under anhydrous conditions, and generally goes forward at ordinary temperatures. Occasionally, the desired quaternary salt precipitates as a gummy solid, in which event a water-miscible organic solvent such as ethanol can be added to dilute the reaction mixture, thereby usually causing the gummy solid to convert to a crystalline white solid of the desired quaternary salt. The quaternary salt can be recrystallized as desired from, for example, absolute ethanol.

The quaternary derivatives of the alkyl-substituted 3-pyrrolidinyl esters of this invention are useful as antisecretory agents, as shown in standard animal tests such as the Shay rat test. For this purpose, the compounds can suitably be administered orally in filled gelatin capsules or as pressed tablets prepared with the customary fillers (lactose, glucose, starch, or the like), binding agents, stabilizing agents, lubricants, and flavors as desired. The compounds are effective at a dosage level between 0.1 and 10 mg. per kg. of body weight in the dog, and at higher levels, of the order of 10 to 50 mg. per kg., in the rat.

Furthermore, a number of the quaternary compounds of this invention are useful as antiperspirant agents when applied topically to the loci to be treated. For this purpose, the compounds can be employed as an aqueous or an alcoholic mixture, suitably in a weight concentration of around 0.5 to 5 percent, or as a solid cream containing around 0.1 to 5 percent by weight of the quaternary compound, preferably in each case in the form of a salt.

The free bases of the alkyl-substituted 3-pyrrolidinyl esters are useful as intermediates in the preparation of the quaternary compounds of this invention. Moreover, they have antisecretory activity, like the quaternary compounds, but are of somewhat less potency. The acid addi-

tion salts of the N-alkyl-substituted 3-pyrrolidinyl esters usually have activity of the same order as the free bases of the esters in respect to antisecretory action, and are further useful in the purification of the free bases and as intermediates in the preparation of the quaternary compounds.

The following specific examples will further illustrate the invention.

EXAMPLE 1

1-Methyl-3-Pyrrolidyl Phenyl-2-Thienylglycolate

A solution of 5 g. of 1-methyl-3-pyrrolidinol and 12.5 g. of methyl phenyl-2-thienylglycolate in 200 ml. of n-heptane is heated to reflux temperature, a trace of sodium methylate is added, and refluxing of the mixture is continued for three hours. A Dean-Stark trap is incorporated in the reflux apparatus to separate and withdraw the methanol produced by the reaction. At the end of the reflux period, the reaction mixture is cooled and extracted two times with 100-ml. portions of 2 N hydrochloric acid. The acid extracts are combined, basified with potassium carbonate, and extracted three times with 50-ml. portions of benzene. The benzene extracts are combined, washed two times with 25-ml. portions of water, and dried. The benzene is removed from the dried extract by evaporation at reduced pressure. The residue is 1-methyl-3-pyrrolidyl phenyl-2-thienylglycolate in the form of a clear liquid.

EXAMPLE 2

1-Methyl-3-Pyrrolidyl Phenyl-2-Thienylglycolate Hydrochloride

1-methyl-3-pyrrolidyl phenyl-2-thienylglycolate, prepared as described in Example 1, is dissolved in ethyl acetate to a concentration of about 20 percent by weight. To the solution is added a small excess of an anhydrous ethanolic solution of hydrogen chloride, whereupon 1-methyl-3-pyrrolidyl phenyl-2-thienylglycolate hydrochloride separates as a white crystalline solid and is removed by filtration.

EXAMPLES 3-5

1-Methyl-3-Pyrrolidyl Phenyl-2-Thienylglycolate Acid Addition Salts

The hydrobromide, the sulfate, and the succinate acid addition salts of 1-methyl-3-pyrrolidyl phenyl-2-thienylglycolate are prepared according to the procedure of Example 2, employing hydrogen bromide, sulfuric acid, and succinic acid, respectively, instead of hydrogen chloride.

EXAMPLE 6

1-Methyl-3-Pyrrolidyl Phenyl-2-Thienylglycolate Methobromide

Five grams of 1-methyl-3-pyrrolidyl phenyl-2-thienylglycolate hydrochloride, prepared as described in Example 2, are dissolved in 50 ml. of water. The aqueous solution is basified by adding solid potassium carbonate with stirring, and the basified mixture is extracted three times with 25-ml. portions of benzene. The benzene extracts are combined, dried with anhydrous magnesium sulfate, and evaporated to dryness. The residue is dissolved in methyl ethyl ketone. Into the resulting solution is bubbled an excess amount of methyl bromide, and the mixture is permitted to stand at room temperature, whereupon a white precipitate appears, consisting of 1-methyl-3-pyrrolidyl phenyl-2-thienylglycolate methobromide. The precipitate is removed by filtration, washed with methyl ethyl ketone, recrystallized from absolute ethanol, and dried.

EXAMPLE 7

Diastereoisomers of 1-Methyl-3-Pyrrolidyl Phenyl-2-Thienylglycolate Methobromide

1-methyl-3-pyrrolidyl phenyl-2-thienylglycolate methobromide is readily separated into two diastereoisomeric fractions by fractional crystallization. The crude mixed

material, prepared as described in Example 6, is dissolved in the minimum quantity of methanol, decolorized with charcoal, diluted with 4 or 5 volumes of ethyl acetate, concentrated on a steam bath until crystals begin to appear, and cooled. The resulting crystals are the alpha diastereoisomer, melting at 210-211°C.

Analysis.—Calcd. for $C_{11}H_{19}NO_3S \cdot CH_3Br$: C, 52.43; H, 5.38. Found: C, 52.16; H, 5.54.

The mother liquor is further diluted with an equal volume of ethyl acetate, concentrated on a steam bath until crystallization begins, and cooled. The resulting crystals, are the beta diastereoisomer, melting at 182-184°C.

Analysis.—Calcd. for $C_{11}H_{19}NO_3S \cdot CH_3Br$: C, 52.43; H, 5.38. Found: C, 52.38; H, 5.43.

The alpha and beta diastereoisomers have different crystal forms and different infrared absorption spectra.

EXAMPLE 8

1-Methyl-3-Pyrrolidyl Phenyl-2-Thienylglycolate Quaternary Salts

The ethiodide, the methochloride, and the methyl methosulfate quaternary salts of 1-methyl-3-pyrrolidyl phenyl-2-thienylglycolate are prepared according to the procedure of Example 6, employing ethyl iodide, methyl chloride, and methyl sulfate, respectively, instead of methyl bromide.

EXAMPLES 9-12

1-Ethyl-3-Pyrrolidyl Phenyl-2-Thienylglycolate and Derivatives

Ethylamine and 1,4-dichloro-2-butanol are reacted according to Pyrrolidinol Procedure II, described hereinabove, to produce 1-ethyl-3-pyrrolidinol. The latter is reacted in equimolar ratio with methyl phenyl-2-thienylglycolate according to the procedure of Example 1 to produce 1-ethyl-3-pyrrolidyl phenyl-2-thienylglycolate as a clear liquid product.

The resulting product is converted via the procedure of Example 2 into 1-ethyl-3-pyrrolidyl phenyl-2-thienylglycolate hydrochloride in the form of a white crystalline solid.

Into a solution of 1-ethyl-3-pyrrolidyl phenyl-2-thienylglycolate in methyl ethyl ketone is bubbled an excess of methyl bromide. The resulting precipitate of 1-ethyl-3-pyrrolidyl phenyl-2-thienylglycolate methobromide is filtered off, washed with methyl ethyl ketone, and recrystallized from absolute ethanol as a white, crystalline solid.

1-ethyl-3-pyrrolidyl phenyl-2-thienylglycolate ethobromide is prepared according to the same procedure, employing ethyl bromide instead of methyl bromide.

EXAMPLES 13 AND 14

1-Methyl-3-Pyrrolidyl Cyclohexyl-2-Thienylglycolate and Methobromide

1-methyl-3-pyrrolidyl cyclohexyl-2-thienylglycolate is prepared and isolated as a clear liquid by the procedure of Example 1, employing 1-methyl-3-pyrrolidinol and methyl cyclohexyl-2-thienylglycolate in equimolar ratio as the reactants.

The resulting product is converted into 1-methyl-3-pyrrolidyl cyclohexyl-2-thienylglycolate methobromide by reaction with methyl bromide according to the procedure of Example 6.

EXAMPLES 15-17

1-n-Butyl-3-Pyrrolidyl Cyclopentyl-3-Thienylglycolate and Derivatives

1-n-butyl-3-pyrrolidyl cyclopentyl-3-thienylglycolate is prepared and isolated as a clear liquid by the procedure of Example 1, employing 1-n-butyl-3-pyrrolidinol and methyl cyclopentyl-3-thienylglycolate in equimolar ratio as the reactants.

The resulting product is converted into 1-n-butyl-3-pyrrolidyl cyclopentyl-3-thienylglycolate hydrochloride in the

form of a white, crystalline solid by reaction with hydrogen chloride according to the procedure of Example 2.

The hydrochloride is converted into 1-n-butyl-3-pyrrolidyl cyclopentyl-3-thienylglycolate methobromide by reaction with methyl bromide according to the procedure of Example 6.

EXAMPLES 18 AND 19

1,5-Dimethyl-3-Pyrrolidyl Bis(2-Thienyl)Glycolate and Methobromide

1,5-dimethyl-3-pyrrolidyl bis(2-thienyl)glycolate is prepared and isolated by the procedure of Example 1, employing 1,5-dimethyl-3-pyrrolidinol and methyl bis(2-thienyl)glycolate in equimolar ratio as the reactants. The 1,5-dimethyl-3-pyrrolidinol employed in the reaction is obtained by the reaction of N-carbethoxymethyl-N-(2-carbethoxypropyl)methylamine and sodium hydride following "Pyrrolidinol Procedure I," described hereinabove.

The resulting product is converted into the corresponding methobromide by reaction with methyl bromide according to the procedure of Example 6.

EXAMPLE 20

1,5,5-Trimethyl-3-Pyrrolidyl Phenyl-2-Thienylglycolate

1,5,5-trimethyl-3-pyrrolidyl phenyl-2-thienylglycolate is prepared and isolated by the procedure of Example 1, employing 1,5,5-trimethyl-3-pyrrolidinol and methyl phenyl-2-thienylglycolate in equimolar ratio as the reactants. The 1,5,5-trimethyl-3-pyrrolidinol employed in the reaction is prepared by the reaction of α,α -dimethyl- β -carbethoxyethyl- α' -carbethoxymethylmethylamine and sodium hydride following "Pyrrolidinol Procedure I."

EXAMPLE 21

1,2-Dimethyl-3-Pyrrolidyl Phenyl-2-Thienylglycolate

1,2-dimethyl-3-pyrrolidyl phenyl-2-thienylglycolate is prepared and isolated by the procedure of Example 1, employing 2.0 g. of 1,2-dimethyl-3-pyrrolidinol and 5.2 g. of methyl phenyl-2-thienylglycolate as the reactants.

EXAMPLE 22

1,2,2-Trimethyl-3-Pyrrolidyl Phenyl-2-Thienylglycolate

1,2,2-trimethyl-3-pyrrolidyl phenyl-2-thienylglycolate is prepared and isolated by the procedure of Example 1, employing 3.0 g. of 1,2,2-trimethyl-3-pyrrolidinol and 6.3 g. of methyl phenyl-2-thienylglycolate as the reactants.

EXAMPLE 23

1,4-Dimethyl-3-Pyrrolidyl Phenyl-2-Thienylglycolate

1,4-dimethyl-3-pyrrolidyl phenyl-2-thienylglycolate is prepared and isolated by the procedure of Example 1, employing 1.0 g. of 1,4-dimethyl-3-pyrrolidinol and 2.7 g. of methyl phenyl-2-thienylglycolate as the reactants.

EXAMPLES 24-27

Methobromides

The phenyl-2-thienylglycolate esters of Examples 20-23 are converted into the corresponding methobromides by reaction with methyl bromide according to the procedure of Example 6.

While the foregoing description represents certain specific embodiments of the invention, it is to be understood that such matters are illustrative only and not by way of limitation. Numerous modifications and equivalents of the invention will be readily apparent to those skilled in the art from the foregoing description.

We claim:

1. 1 - methyl - 3-pyrrolidyl phenyl-2-thienylglycolate methobromide.
2. The alpha diastereoisomer of 1-methyl-3-pyrrolidyl phenyl-2-thienylglycolate methobromide.
3. The beta diastereoisomer of 1-methyl-3-pyrrolidyl phenyl-2-thienylglycolate methobromide.

4. A salt of 1,1-dimethyl-3-pyrrolidyl phenyl-2-thienyl-glycolate with a pharmaceutically acceptable acid.
